UNITED STATES PATENT OFFICE

WILLIAM L. MYERS, OF NEWARK, AND GEORGE D. HARRISON, OF BELLEVILLE, NEW JERSEY, ASSIGNORS TO L. A. MYERS, JR., INC., OF NEWARK, NEW JERSEY, A CORPORATION OF NEW JERSEY

ATTACHMENT FOR SHOE ORNAMENTS

Application filed March 26, 1929. Serial No. 350,006.

This invention relates to means for attaching an ornament commonly referred to as a buckle to the forward portion of a pump, slipper or the like; and has for its object to provide an attachment by which an ornament of the common construction found on the market may be snapped into position on the shoe.

A further object of the invention is to provide a construction of attachment by which buckles or shoe ornaments may be interchangeable one with another on the shoe.

A still further object of the invention is the provision of an attachment which will be narrow in width so as not to interfere with the stretch of an elastic insert or goring to which it may be attached at the forward edge of the pump or slipper.

With these and other objects in view, the invention consists of certain novel features of construction, as will be more fully described, and particularly pointed out in the appended claims.

In the accompanying drawings:

Figure 1 is a perspective view of the forward portion of a ladies' pump or slipper with ornament attached thereto.

Figure 2 is a perspective view of the shoe with the ornament removed, showing the plate attachment member as secured to the shoe.

Figure 3 is a perspective view of the plate attachment member.

Figure 4 is a plan view showing the plate attachment member as sewed to the portion of the shoe to which it is secured.

Figure 5 is a side view thereof showing the shoe indicated in section.

Figure 6 shows the attachment as stapled onto the shoe as distinguished from the sewing in Figures 4 and 5.

Figure 7 is a modified form of plate attachment member showing integral spurs formed on the edges thereof for securing the same to the shoe.

Figure 8 is a sectional view of Figure 7 showing the plate member attached to a portion of the shoe.

Figure 9 is a still further modification showing the spurs for attaching the plate

member to the shoe as formed within the peripheral edges of the device and also showing a modified form of means for preventing sliding movement of the buckle bar on the plate member.

Figure 10 is a sectional view of Figure 9 showing the same as attached to a portion of the shoe.

Figure 11 is a sectional view of the buckle in its position in engagement with the attachment plate.

Figure 12 is a sectional view thru the spring fingers such as illustrated in the previous figures.

Figure 13 is a back view of the buckle showing the bar as notched on its edges to cooperate with the V-shaped detents shown in Figures 3, 4, 5, 6, 7, and 8, for holding the same against sliding movement.

Figure 14 is a back view of a buckle provided with holes the middle one of which cooperates with the means shown in Figures 9, 10, and 11 to prevent sliding of the same on the attachment plate member.

Figure 15 is a plan view of the plate attachment member with the ornamental plate portion of the buckle removed showing the notched bar in engagement with its fastening plate member.

Figure 16 is a view similar to Figure 15 showing the buckle bar of Figure 14 in engagement with the form of holding means shown in Figures 9, 10, and 11.

Figure 17 is a sectional view of a still further modified form showing the hole in the bar of the buckle in engagement with the pressed out detent shown on the plate attachment member.

Figure 18 is a perspective view of still further modification showing a different form of resilient holding means for engagement with the bar of the buckle.

Figure 19 is a perspective view similar to Figure 18 showing the bar as engaging the resilient means.

Figure 20 is a perspective view of a still further modification having spring fingers raised from the stock of the plate and disposed in opposite directions.

Figure 21 is a view similar to Figure 20

showing the bar as engaged by the spring fingers.

Figure 22 is a perspective view of a still further modified form of plate attachment member.

Figure 23 is a perspective view showing the plate member in Figure 22 as engaging the bar of the buckle there being two sets of fingers formed to engage the bar on opposite sides.

Figure 24 is a section illustrating a modification with the fingers as illustrated in Figures 2 to 17 as rolled outwardly instead of inwardly.

15   Ornament which are used on the forward portion of a shoe are commonly provided with a bar spaced from the back thereof formed with openings adapting them to be sewed onto the shoe. It is found, however, 20   desirable to provide a means by which these buckles may be quickly snapped upon the shoes and interchanged at will without any material alterations of the back bar except such as may be made with a pair of pliers or 25   the like at a place removed from the factory and in order to provide such a construction and one which when in place will not limit the extendability of the goring or elastic insert at the front portion of the shoe. We have 30   provided a plate which is narrow in construction to be attached to the shoe with resilient fingers provided on its front surface to receive the back bar of the buckle which may be snapped into place, and we have provided 35   a means which may cooperate with an opening in the buckle bar or with a notch which may be easily formed in the back bar by pliers to prevent the buckle from moving longitudinally on the attachment plate member; 40   and the following is a detailed description of the present embodiment of the invention illustrating the preferred means by which these advantageous results may be accomplished:

45   With reference to the drawings, 10 designates a shoe of the pump or slipper type worn by ladies with an ornament 11 in place thereon. This ornament has a front plate 12 with a cross bar 13 spaced from the back of the 50   ornament which is customarily provided with sew holes 14, 15, and 16. The back bar 13, however, may be notched as at 17 by a pair of pliers for the purpose hereinafter specified.

55   The plate attachment member is formed of sheet stock with a base or body portion 18 and side portions 19 causing the same to be generally channel shape in cross section, to receive the bar 13. Spaced along the opposite side edges of the body portion of the plate are spring fingers 20, rolled inwardly toward or outwardly from each other to provide resilient portions between which the bar 13 of the buckle or ornament may snap into position. There are also provided V-

shaped fingers 21 on the opposite edges of the plate folded inwardly toward each other to engage in the notches 17 in the bar of the buckle to prevent sliding movement of the bar along the plate member after snapped 70 into position between the resilient fingers 20. Or as an alternative, the plate attachment member may be provided with a resilient detent 2 cut and raised from the stock of the base or body portion 18 to engage in the opening 15 of the bar of the ornament as illustrated in Figure 11, or the detent may be merely raised from the stock of the body to engage the hole 15 in the bar as illustrated in Figure 17, any of which various means prevent a 80 relative movement of the bar and plate beneath the spring fingers.

In order that the attachment plate may be secured to the shoe, we may provide holes 24, as illustrated in Figure 3, for sewing the 85 same in position or a recess 25 extending laterally of the attachment plate may be provided to receive the threads 26 which are passed about a portion 27 of the shoe to secure the plate in its position, the recess being provided so as to permit the bar to contact with the back or body portion 18 of the plate and not interfere with its clamping by the spring fingers.

In still other instances, the plate member 95 may be attached to the portion 27 of the shoe by a staple 28, as illustrated in Figure 6, while in still other instances spurs 29 and 30 may be provided on the marginal edges of the plate member to pierce a portion of the shoe member 27 and be bent over its back surface to secure the same thereto or the spurs 31 and 32 may be cut from the stock of the plate within its periphery and bent to pierce the shoe portion 27 and extend over the back 105 thereof as at 33 to secure the plate member in position.

In some cases we have found that the resilient means for receiving the back bar may be formed by cutting a portion of the plate and raising it to provide spring fingers 34 and 35 oppositely disposed to receive the bar 13 between them by a relative twisting movement, between the plate and bar, the plate 36 being provided with suitable sewing holes or other convenient means as previously indicated for attachment to the shoe.

A still further modification of this type of fingers is illustrated in Figures 22 and 23, in which spring fingers 38 are formed as straps leaving resilient portions 39 to be suitably bent to engage the opposite surface of the bar to increase the friction thereon which will assist in preventing movement of the bar on the plate.

In still another modification, the resilient holding means is formed as illustrated in Figures 18 and 19 in which the plate 40 is slit and straps 41 raised therefrom to receive beneath them the resilient wire portion 42 130

bent to engage the bar 13 at spaced portions therealong and beneath which the bar may be moved by sidewise movement to resiliently and frictionally hold the same in position.

5 The plate 40 of this construction is provided with suitable means as heretofore described for attaching the same to a shoe as desired.

It will be understood that in the type of construction in which the bar is pressed firmly against the plate by the resilient fingers such as illustrated in sheet 2 of the drawings, Figures 18 to 23 inclusive, that it is often not necessary to provide means to prevent a sliding of the parts due to the 15 strong friction of engagement thereof.

The foregoing description is directed solely towards the construction illustrated, but we desire it to be understood that we reserve the privilege of resorting to all the mechanical 20 changes to which the device is susceptible, the invention being defined and limited only by the terms of the appended claims.

We claim:

1. In combination, a shoe ornament having 25 a retaining element spaced from the back thereof, a plate, means for securing the plate to a shoe, and sets of cooperating resilient aligning and gripping members positioned on said plate for frictionally gripping said 30 retaining element between them at longitudinally spaced points to releasably attach the shoe ornament in aligned position on the shoe.

2. In combination, a shoe ornament having 35 a retaining element spaced from the back thereof, a plate, means for securing the plate to a shoe, and sets of resilient aligning and gripping members on said plate each set spaced apart and open at the front between 40 them between which the retaining element may be snapped from the front to be frictionally gripped for releasably attaching the shoe ornament in aligned position on the shoe.

45 3. In combination, a shoe ornament having a retaining element spaced from the back thereof, a plate, means for securing the plate to a shoe, and sets of resilient aligning and gripping members on said plate each set 50 spaced apart and open at the front between them between which the retaining element may be snapped from the front to be frictionally gripped for releasably attaching the shoe ornament in aligned position on the 55 shoe, and a projection for preventing endwise displacement of said retaining element on said plate.

In testimony whereof we affix our signatures.

60 WILLIAM L. MYERS.
GEORGE D. HARRISON.
